UNITED STATES PATENT OFFICE

GEORGE E. NORRIS, OF COLUMBUS, OHIO

VENDING MACHINE

Application filed April 20, 1931. Serial No. 531,413.

This invention relates to improvements in vending machines and particularly to vending machines of the coin operated type wherein merchandise such as peanuts, hard candy or other comestibles of like character are vended. Recently it has been proposed to insert prizes, such as small and cheap articles of jewelry, in the candy contained in the hopper of the machine so that from time to time in the operation of the machine one or more of such prizes will be delivered with each purchase of peanuts or candy.

The vending machine patented by me on August 14, 1923, which has been generally shown in the drawings of this application, is particularly suitable for the vending of such articles. However, it has been found that the production of these small metallic objects may result in the clogging of the machine or interfere with the working mechanism thereof. Particularly, the objects are apt to engage or become caught between the rotatable carrier used in this machine and the discharge chute thereof.

It is an object of this invention to prevent the interference of such articles of jewelry and to provide means for the uninterrupted operation of the carrier and the proper delivery of the merchandise by the machine.

It is also an object of the invention to provide a rotatable carrier of the apparatus with adjustable pockets therein so that the same may be varied in size to accommodate different kinds of articles.

For a further understanding of the device, reference is to be had to the accompanying drawings, wherein:

Figure 1 is a vertical sectional view taken through the lower portion of the vending machine showing the vending mechanism thereof,

Figure 2 is a horizontal sectional view taken on the line 2—2 of Figure 1,

Figure 3 is a transverse vertical sectional view taken on the line 3—3 of Figure 1,

Figure 4 is a fragmentary detailed vertical sectional view taken on the line 4—4 of Figure 2,

Figure 5 is a detail view of the rotatable

carrier used in the machine with parts broken away to show underlying structure,

Figure 6 is an edge elevation thereof,

Figure 7 is a fragmentary detailed view showing the pockets of the carrier adjusted to accommodate such articles as chewing gum balls or the like.

Referring more particularly to the drawings, there is disclosed generally the structure set forth in my aforementioned patent and it is therefore believed unnecessary to enter into a minute description thereof which is formed to embody a base 1 from which arises the side walls comprising the cabinet 2 which may be provided with one or more transparent walls 3 in order that the merchandise within the cabinet may be viewed from the exterior thereof. The upper end of the machine is closed by any suitable top (not shown) and which may be removed for the insertion of the merchandise to be vended. Arranged at a distance substantially midway of the height of the cabinet 2 is a horizontal partition 4, rigidly retained in an applied position and formed to include a discharge opening 5 communicating with the vending mechanism of the machine. This partition serves as the bottom of the merchandise container cabinet and supports the greater bulk of the merchandise.

Positioned within the machine or cabinet and arranged beneath the partition 4 is a fixed shelf 6 which is provided with an upstanding centrally located post 7, the latter being received within the hub 8 of a rotatable carrier 9. The carrier, as shown more particularly in Figure 5, is provided with a plurality of compartments 10, into which the merchandise is permitted to gravitate from the upper portion of the machine through the opening 5 of the partition 4. The carrier in this instance is formed to include a toothed edge 11 disposed for engagement with the teeth of the gear 12, which is carried by the inner end of an operating shaft 13, journaled horizontally for rotation and having its outer end equipped with a manipulating handle 14, which handle is positioned beyond the walls of the machine. It will be seen that by rotating the shaft 13 the carrier 9 will be rotated about the post in

order that the filled compartments 10 of the carrier may be brought successively into registration with the discharge opening 15 formed in the shelf 6. The carrier may discharge its contents through the opening 15 and into the chute 16, which is downwardly inclined and projects through the front wall of the cabinet, the lower end of the chute being provided with the usual pivoted door 17 which when lifted will permit of the convenient removal of the contents of the chute.

The coin controlled operating mechanism of the machine is formed to include a plate 18 provided with an inwardly projecting flange 19 secured as at 20 to the shelf 6. The plate is further formed to include bearings 21 and 22 for the rotatable support of the shaft 13 and to include a coin receiving chute 23 which terminates at its upper end into a forwardly directed circular opening 24 through which the coins may be inserted to be deposited within the chute 23. Formed with the shaft 13 is a ratchet wheel 25 which has its periphery provided with an arcuate recess 26, terminating in shoulders 27. This recess is adapted to receive the arcuate shoe extension 28 provided upon a pivoted pawl 29. This pawl is pivoted as at 30 to the rear face of the plate 18 and the shoe extension 28 is disposed to pass through an opening 31 provided in the plate 18, the opening 31 being of sufficient size as to permit of the oscillation of the pawl 29 and a consequent moving into or out of locking engagement with the ratchet wheel 25. The shoe extension 28 is united with the body of the pawl by means of the laterally extending connection 32 which is disposed within the chute 23 and extends across the chute between the inner wall thereof and the ratchet wheel 25. The latter is provided with a fixed projection 33, which is positioned within the chute 23 and is located immediately to one side of the terminating end of the latter.

By this construction it will be noted that when a coin is deposited within the chute 23, the same will fall downwardly until it engages with the operating shaft 13 as disclosed more fully in Figure 3 and will be positioned so that the periphery of the coin will be located continuous to the projection 33 and the edge of the connection 32, which latter is located on a plane slightly above the true center of the coin. Thus by rotating the shaft 13 in a clockwise direction, the projection 33 of the ratchet wheel 25 will engage the coin and force the latter towards the connection 32 elevating the same and the pawl 29 bodily and causing its shoe extension 28 to be lifted out of the recess 26 permitting said extension to clear the shoulders 27 so that the ratchet wheel 25 and consequently the operating shaft 13 may be freely rotated. It will be obvious that the rotation of the shaft 13 will bring the successive compartments 10 of the carrier into alignment with the discharge opening 15 pro-

vided in the shelf 6. To prevent rearward or backward rotation on the part of the operating shaft 13, the ratchet wheel 25 is also provided with teeth 34 which are adapted to engage a spring pressed dog 35 pivoted as at 36 to the plate 18. By the provision of the teeth 34 and the dog 35 the shaft 13 must be given a complete revolution after movement thereto has been initiated. During this rotation the coin will free itself from the connection 32 and deposit itself into the lower part of the machine and the shoe extension 28 is then again, of course, positioned within the recess 26 due to the provision of the spring 37 connected to the pawl 29, to again lock the machine after a complete operation.

All of the foregoing mechanism described has been set forth in my former patent and therefore no claim is laid thereto in this case. However, to make use of this mechanism for vending merchandise on the order of peanuts, small hard candy and the like with prizes or cheap jewelry therein as stated in the objects, a change in the rotatable carrier as well as in the partition wall 4 was necessary. The change includes the forming of the partition wall with a compartment 38 which is arranged above the discharge opening 15 and has its top wall 39 spaced a considerable distance from the top of the carrier 9 and one of its sides closed by the arcuate wall 40, the ends of this compartment being closed by vertically arranged gates 41 pivoted as at 42 and held against shoulders 43 by means of coil springs 44. The springs 44 are of sufficient strength to maintain the gates 41 in a vertical position and against the shoulders 43 under normal conditions when the merchandise within the pockets and a piece of jewelry or other article therein is below the top of the carrier or substantially even therewith. However should the article extend a distance above the upper edge of a pocket the gate or gates 41 are free to swing in the direction of the rotation of the carrier and permit the jewelry to pass thereunder preventing the same from being broken or hinder the operation of the machine. It has also been found desirable to provide a compartment 38 with an intermediate spring pressed gate 45 which will act as an agitator and tend to aid in positioning the jewelry correctly within the pocket before being discharged from the apparatus. In case such jewelry should become caught in the pocket and fail to drop into the discharge chute of the machine, the gate positioned in the outlet side of the compartment will permit the jewelry to again follow the carrier until it becomes so positioned that it will be delivered from the apparatus. The gates which are held in a vertical position to close the compartment 38 will, of course, under normal conditions, hold the peanuts out of the discharge compartment and as the gates are po-

sitioned radially from the center of the pivotal point of the carrier, the lower edge of the gates will be arranged in alignment with the radial side walls of the pockets 10 of the carrier.

In order to regulate the amount of merchandise to be vended by the machine the carrier is formed so that the sides of the pockets therein may be increased or decreased depending upon the class of merchandise to be vended. To this end the carrier is formed to comprise two parts adjustable with respect to one another and each formed to include radial pocket defining fins 46 and 47. The fins 46 of the lower part 9' are positioned between the walls 47 of the upper part 9 or main carrier, and therefore by rotating the lower section 9' relative to the upper section the fins will serve to increase or decrease the size of the pockets as will be readily understood by referring to Figures 5 and 7 of the drawings. The fins 46 of the lower section may also be provided with projections 48 and when the fins 46 have been moved relative to the fins of the upper section as disclosed in Figure 7, said projections will be located within the opening formed in the top section and thereby decreasing said pocket in size lengthwise or radially making the pocket suitable for such products as chewing gum or candy balls. The adjustment between the sections 9 and 9' may be maintained by forming the lower section along its upper edge with a plurality of notches 49 for the reception of a pin or projection 50 depending from the lower edge of the upper section. Thus in order to adjust the two sections relative to one another it will only be necessary to spread the same apart a distance substantially equal to the depth of the notches 49 and rotate the same axially and as the two sections are confined between the partition wall 4 and the shelf 6 it will be seen that this adjustment will be maintained.

From the foregoing description taken in connection with the accompanying drawings, it will be seen that the present invention provides a vending apparatus wherein peanuts, small hard candy or the like may be vended and wherein articles of jewelry or other prizes contained within the merchandise may be vended and be delivered with each purchase. The machine is so formed that such prizes may be delivered from the apparatus without the danger of clogging the machine or interfering with the proper operation thereof. The rotatable carrier of the machine is also formed so that various amounts of such merchandise may be delivered or to handle a single article of comparatively large size on each purchase. By the introduction of such prizes in the merchandise, it will be obvious that the sales thereof will be stimulated.

What is claimed is:

1. In a coin controlled vending machine including a merchandise containing hopper, a partition wall at the lower end of said hopper formed with an opening therein, a rotatable carrier arranged below said wall and provided with pockets adapted for registration with said opening, a discharge chute below said carrier, means for rotating said carrier to align the pockets with said opening and chute, and spaced vertically arranged spring pressed gates positioned below said wall and above said carrier, said gates together with said wall forming a compartment above said chute and arranged to swing in a direction of rotation of said carrier, said gates serving to permit of the passage of merchandise contained within said pockets and extending a distance above the upper surface thereof to be discharged into said chute.

2. In a coin controlled vending machine including a merchandise containing hopper, a horizontally arranged partition wall at the lower end of said hopper and provided with an opening therein, a rotatable carrier disposed below said wall and formed with pockets adapted for registration with said opening upon the rotation of said carrier, a discharge chute below said carrier, a portion of said partition wall being spaced from the top of the carrier to provide a compartment above and in alignment with said chute, and a vertically arranged hinged gate positioned at the entrance of said compartment and free to swing inwardly thereinto upon contact with merchandise positioned within the pockets of said carrier extending above the latter.

3. In a coin controlled vending machine including a merchandise containing hopper, a horizontally arranged partition wall at the lower end of said hopper and formed with an opening therein, a rotatable carrier disposed below said wall and provided with pockets adapted for registration with said opening upon the rotation of said carrier, a shelf below said carrier having a discharge opening formed therein in alignment with the pockets of said carrier upon the rotation of the latter, said partition wall having a portion thereof disposed spaced from the top of said carrier to provide a compartment above and in alignment with said discharge opening formed in said shelf, said compartment having an open communication with the interior of said hopper, and a hinged gate positioned at the entrance opening connecting said compartment with said hopper, said gate being free to swing inwardly into said compartment upon contact with merchandise extending above said carrier when the latter is rotated.

4. In a coin controlled vending machine including a merchandise containing hopper,

a horizontally arranged partition wall at the lower end of said hopper and formed with an opening therein, a movable carrier disposed below said wall and provided with 5 pockets adapted for registration with said opening upon the movement of said carrier, a shelf arranged below said carrier formed with a discharge opening therein, said partition wall having a portion therein spaced 10 from the top of said carrier to provide a compartment above and over the discharge opening formed in said shelf, the ends of said compartment being opened to the interior of said hopper, and vertically arranged 15 spring pressed gates closing the ends of said compartment, said gates being free to swing in a direction of movement of said carrier and serving to allow the passage of merchandise extending above the upper surface of said 20 carrier to enter said compartment.

5. In a coin controlled vending machine including a merchandise containing hopper, a horizontally arranged partition wall arranged at the lower portion of said hopper 25 and formed with an opening therein, a rotatable carrier disposed below said wall and provided with pockets adapted for registration with said opening upon the rotation of said carrier, a shelf serving as a bottom for 30 said pockets positioned below said carrier and provided with a discharge opening therein, said partition wall being spaced from the top of said carrier to provide a compartment above the discharge opening formed in said 35 shelf, said compartment having its ends open to said hopper, and hinged spring pressed gates closing the ends of said compartment.

6. In a coin controlled vending machine including a merchandise containing hopper, 40 a horizontally arranged partition wall at the lower end of said hopper formed with an opening therein, a rotatable carrier disposed below said wall and provided with pockets adapted for registration with said opening 45 upon the rotation of said carrier, said carrier being formed of two parts each provided with radially extending fins which together form the walls of said pockets, upon the rotation of said parts relative to one another 50 said fins may be spaced at various distances from one another to increase or decrease the size of said pockets.

7. In a coin controlled vending machine including a merchandise containing hopper, 55 a movable carrier arranged below the discharge end of said hopper, a discharge chute below said carrier, and resiliently movable gate means mounted at a fixed point and arranged between said hopper and carrier 60 for permitting merchandise contained within said carrier and extending above the upper surface thereof to move said gate means to an extent permitting of the delivery of 65 the merchandise to said discharge chute.

8. In a coin controlled vending machine, a

merchandise containing hopper having a discharge opening at its lower end, a movable carrier arranged below said opening, a discharge chute below said carrier, and resiliently mounted gate means positioned at a fixed point and arranged between said hopper and carrier for permitting merchandise contained in and extending above said carrier to move said gate means a distance permitting of the passage of the merchandise 70 to said discharge chute.

In testimony whereof I affix my signature.
GEORGE E. NORRIS.
